2 SHEETS—SHEET 2.

E-i-g-h-t

Eig. 4.

Ein-g-e-

A technical drawing of a circular component, likely a wheel or hub. The outer ring is divided into four segments by a central hole and four radial lines. The segments are labeled with the numbers 35, 43, and 45. There are also two small rectangular features with the number 0 on them, one on the left and one on the right. The drawing is done in black and white, with a focus on the geometric shapes and labels.

UNITED STATES PATENT OFFICE

FRITZ S. BECKMAN, OF GRUNDY CENTER, IOWA

AUTOMOBILE-SIGNAL.

1,253,124.

Specification of Letters Patent.

Patented Jan. 8, 1918.

Application filed January 17, 1917. Serial No. 142,864.

To all whom it may concern:

Be it known that I, Dr. FRITZ S. BECKMAN, a citizen of the United States, residing at Grundy Center, in the county of Grundy and State of Iowa, have invented certain new and useful Improvements in Automobile-Signals; and I do hereby declare the following to be a full, clear, and exact description of the invention, such as will enable others skilled in the art to which it appertains to make and use the same.

This invention relates to an automobile signal and has for one of its objects the provision of a device of this character, whereby the operator of the automobile may notify the traffic in front and rear thereof in which direction a turn is to be made.

Another object of this invention is to provide a casing having direction indicating rollers therein adapted to be electrically operated to show the direction indicating characters through slots in the casing.

A further object of this invention is to provide electromagnets located in the casing which when energized are adapted to rotate gears which in turn rotate the rollers in one direction or into signaling position to display through the slots of the casing the direction indicating characters.

30 A further object of this invention is the provision of means for returning the rollers to their normal position or into non-signaling position.

A still further object of this invention is the provision of an automobile signal of the above stated character, which shall be simple, durable and efficient, and which may be manufactured and sold at a comparatively low cost.

40 With these and other objects in view as will become more apparent as the description proceeds, the invention consists of certain novel features of construction, combination and arrangement of parts as will be hereinafter more fully described and claimed.

For a complete understanding of my invention, reference is to be had to the following description, and accompanying drawings, in which:

Figure 1 is a vertical sectional view of an automobile signal constructed in accordance with my invention.

55 Fig. 2 is a longitudinal sectional view of the same,

Fig. 3 is a transverse sectional view illus-

trating the means for returning the rollers to non-signaling position,

Fig. 4 is a perspective view of the casing,

Fig. 5 is a fragmentary perspective view of a steering wheel and steering post illustrating contacts thereon for automatically operating the automobile signal,

Fig. 6 is a detail sectional view taken on the line 6—6 of Fig. 5,

Fig. 7 is a plan view of a steering wheel illustrating a modified form of means for operating the automobile signal,

Fig. 8 is a diagrammatical view of the wiring diagram,

Fig. 9 is a detail sectional view illustrating a bolt for connecting the bars to the gears.

Referring in detail to the drawings, the numeral 1 indicates a substantially rectangular casing having a pair of parallel and relatively spaced slots 2 formed in the front wall thereof. Mounted within the casing 1 are supporting brackets 3 and 4 to which are journaled gear wheels 5 and 6. Direction indicating rollers 7 and 8 are journaled to the supporting brackets 3 and 4 and the roller 8 has a gear 9 which meshes with the gear 5. The roller 7 has a gear 10 which meshes with the gear 6. The rollers 7 and 8 extend parallel with the slots 2 of the casing 1 and each have direction indicating characters printed or otherwise applied thereon, such as "Right" and "Left." A pair of relatively spaced and electrically connected magnets 11 are secured within the casing and have an armature plate 12 overlying them which is supported by a bar 13 that is pivoted to standards 14 secured to the casing. The free end of the bar 13 has a pin 15 pivoted thereto which extends into an aperture in the gear 5, so that when the magnets 11 are energized, the bar 13 is moved downwardly rotating the gear 5 which in turn rotates the roller 8 bringing the direction indicating characters thereon in view through one of the slots 2 of the casing, whereby the traffic can be notified that the automobile is going to turn to the left.

105 A pair of relatively spaced and electrically connected magnets 15 are secured within the casing 1 and are overlain by an armature plate 16 that is carried by a bar 17. One end of the bar 17 is pivoted to standards 18 which are secured to the casing. A pin 19 is pivoted to the free end

of the bar 17 and extends into an aperture in the gear 6, whereby upon energizing the magnets 15, the gear 6 will be rotated, which in turn rotates the roller 7 bringing the 5 direction indicating characters thereon in view through one of the slots of the casing 1.

Coiled springs 20 are secured to the supporting brackets 3 and 4 and have their 10 free ends connected to the gears 5 and 6, whereby when the gears are rotated to move the direction indicating characters into signaling position or into view through the slots 2 of the casing, the gears 5 will be 15 turned against the tension of the spring and as soon as the electric magnets are deenergized, the springs 20 return the gears 5 to their normal position, which returns the direction indicating characters into a non- 20 signaling position.

Partitions 21 and 22 are formed in one end of the casing to form chambers 23 and 24. The chambers 23 and 24 in the front walls thereof have substantially rectangular 25 openings, which are closed by colored glass plates 25 and 26. Secured within each of the chambers 23 and 24 are sockets 27 which have electric lamps 28 and 29 mounted therein. The electric lamps are electrically connected with the magnets 11 and 15 so that 30 when the magnets are energized, the electric lamp connected to the respective magnets will be illuminated so as to make the signal visible at night time. The glass 25 is preferably colored blue while the glass plate 26 is preferably colored yellow so that the 35 traffic may determine in which direction the automobile is going to turn, either to the right or left.

40 In reducing my invention to practice, one of the casings 1 are secured to each end or to the front and rear of the automobile and each are placed in electrical circuit with each other, so that when the signal is displayed 45 within the casing upon the front end of the automobile, a corresponding signal will be displayed in the rear of the automobile.

Referring to Fig. 8 in which the wiring diagram is disclosed, the magnets 11 are 50 electrically connected together and have connected thereto conductors 31 and 32. The conductor 32 is connected to the electric lamp 28, which has connected thereto a conductor 33. The conductor 33 is connected to a 55 storage battery 34. The conductor 31 is connected to a switch 35. A conductor 36 is connected to the switch 35 and to the magnets 11 located in the rear casing 1 mounted upon the rear end of the automobile. The 60 last mentioned electric magnets 11 are connected to the electric lamps 28 located within the rear casing and which has connected thereto, a conductor 37 that is connected to the storage battery 34, whereby upon closing 35 the switch 35, the magnets 11 will be ener-

gized operating the roller 8 to bring the direction indicating characters thereon in view through one of the slots of the casing, both in the front and rear of the automobile, simultaneously. When the magnets 11 are 70 energized, the electric lamps 28 are also illuminated which illuminates the yellow glass plate 26 in the chamber 24 making the signal visible at night time. A conductor 38 is connected to the conductor 33 and to 75 the electric lamps 29 located in the front casing. A conductor 39 is connected to the conductor 37 and to the electric lamps 29 located in the rear casing. The electric lamps 29 located in the front and rear casings are connected to the pairs of magnets 15 by conductors 40 and 41. Connected to the pairs of magnets 15 located in the front casing, is a conductor 42 which is connected to a switch 43. Connected to the switch 43 80 is a conductor 44, which connects to the magnets 15 located in the rear casing, whereby upon closing the switch 43, the magnets in the front and rear casings will be simultaneously energized to operate the rollers 7 85 to bring the direction indicating characters thereon in registration with the slots of the casing. The electric lamps 29 located in the front and rear casings will be simultaneously illuminated with the magnets 15. The 90 switches 35 and 43, if desired, may be mounted upon the steering wheel 45 of the automobile, as clearly illustrated in Fig. 7, whereby the operator may operate either of the switches when desiring to operate the 95 signal.

Referring to my modified form of invention as illustrated in Fig. 5, in which means are disclosed for automatically operating the signal upon the turning of the steering wheel, consists of a contact 46 secured to the steering post housing 47, which remains stationary. Mounted upon the steering wheel is a pair of relatively spaced contacts 48 and 49, whereby upon turning the steering wheel 105 to steer the automobile, either of the contacts 48 or 49 will move into an engagement with the contact 46 and complete an electric circuit to the signal for operating the rollers 110 therein.

115 While I have shown and described the preferred embodiment of my invention, it will be understood that minor changes in construction, combination and arrangement of parts may be made without departing 120 from the spirit and scope of the invention as claimed.

What is claimed is:

An automobile signal comprising a casing 125 having slots in the front wall thereof, direction indicating rollers journaled in the casing and extending parallel with the slots, magnets located in said casing, standards secured in said casing, bars pivoted to the standards and overlying the magnets, gears 130

journaled in the casing, and having apertures therein, pins pivoted to the free ends of the bars and extending into the apertures of the gears, and gears secured to the ends 5 of the rollers and in mesh with the first mentioned gears, and means for energizing the magnets to rotate the rollers.

In testimony whereof I affix my signature in presence of two witnesses.

Dr. FRITZ S. BECKMAN.
